UNITED STATES PATENT OFFICE.

HANS AUGUST RICHTER, OF POTTSVILLE, PENNSYLVANIA.

CURTAIN-HOLDER.

1,147,548.

Specification of Letters Patent. Patented July 20, 1915.

Application filed December 22, 1914. Serial No. 878,542.

To all whom it may concern:

Be it known that I, HANS AUGUST RICHTER, a citizen of the United States, residing at Pottsville, in the county of Schuylkill and State of Pennsylvania, have invented new and useful Improvements in Curtain-Holders, of which the following is a specification.

The present invention relates to curtain holders and has particular reference to that class of devices designed to drape the curtain at the side of the window.

The primary object of the invention resides in the provision of a device of the above mentioned character, wherein the hook-like portion for holding the folds of the curtain is closed by the window casing to prevent casual separation of the curtain therefrom, and yet permitted to yield sufficiently to provide an entrance passage for the curtain.

I further aim to provide a device of this character constructed from a single length of resilient wire, wherein the bill of the hook-like portion is formed by the continuation of the wire, with a view of eliminating any sharp projections that would tear or otherwise injure the curtain by coming in contact with the same while inserting or removing the curtain from the device.

In the drawing forming a part of this application like numerals of reference indicate similar parts in the several views and in which:

35 Figure 1 is a perspective view of a window casing showing my device applied. Fig. 2 is a horizontal sectional view through the casing with my device applied thereto, the dotted lines showing the manner of 40 spreading the device to provide an entrance passage.

Referring more particularly to the drawing 5 indicates a plate constructed from any suitable material, and having its upper and 45 lower edges bent to provide the eyes 6 for the reception of the free ends of the holder proper.

The holder proper is constructed from a single length of resilient material, preferably wire to provide a hook-like element 7, the wire being bent intermediate its length to provide spaced parallel strands 9 disposed in superimposed relation. It is of course to be understood that there are to be two of

these elements employed, one at each side 55 of the window casing, the plates 5 being adapted to be secured to the outer edge of the window casing by suitable fastening elements 10 in the manner shown. The relative lengths of the opposite side portions of 60 the hook element are such, that the bill of the hook normally contacts the window casing thereby closing the hook, and preventing casual separation of the curtain from the holder while being brushed or under any 65 other condition. By reason of the fact that the device is constructed from resilient material, the free end of the hook is permitted to yield sufficiently to provide an entrance 70 passage for the curtain, as shown in dotted lines in Fig. 2.

It will be further noted that the bill portion 11 of the hook is formed by the continuation of the wire to provide a curved surface so as not to mar the window casing, 75 and also with a view of eliminating sharp projections that would tear or otherwise injure the curtain by catching in the same while the curtain is being inserted or removed from the holder. The construction 80 is extremely simple in its nature and one which may be readily and easily manipulated in the manner described.

It is believed that from the foregoing description the nature and advantages of the 85 invention will be readily understood without requiring a more extended explanation and therefore the same has been omitted.

What I claim is:—

A curtain holder for windows, including 90 a plate adapted to be secured to the inner side of the window casing and having its opposite edges formed to provide eyes, a hook-like element constructed from a single length of resilient wire bent upon itself to 95 provide superimposed spaced strands, the free ends of which are adapted to be removably positioned within said eyes, and the bill of said hook normally contacting said casing, and adapted to yield to provide an entrance 100 passage for the curtain.

In testimony whereof I affix my signature in presence of two witnesses.

HANS AUGUST RICHTER.
